UNITED STATES PATENT OFFICE.

CHARLES F. HARTMAN, OF LOS ANGELES, CALIFORNIA.

LEAD PENCIL WITH EXTERNAL FEED.

Application filed September 29, 1925. Serial No. 59,313.

My invention relates to improvements in writing and marking instruments in which individual graphite or other writing bars are inserted and then fed by hand by operating an external knob. The objects incorporated in my improvement are:—first, to enable the use of writing leads of oblong cross section adapted for the carpenter or other trades; second, to quicken the feeding action by simply pressing a button; third, to save time in refilling when a new lead of full length is again inserted; and fourth, to provide a collar or lead outlet terminal of a more resistive material which is not so easily marred by the use of abrasives employed to keep the lead point sharp.

I attain these objects by the mechanism illustrated in the accompanying drawing, in which:

20 Figure 1 is a vertical section of a pencil having an external feed, with a knurled button on top which can be pressed down to feed the lead out, and retained after partial rotation during the time a new lead is being inserted;

Fig. 2 is an end elevation of Fig. 1;

Fig. 3 is a horizontal section taken through the pencil on the line 3—3 of Fig. 1.

30 Fig. 4 is a horizontal section taken through the pencil on the line 4—4 of Fig. 1.

Fig. 5 is another embodiment of my invention showing a pencil with external feed and is a vertical section taken on the line 5—5 of Fig. 6 showing a button on top to be pressed down when feeding the lead out and to be kept withdrawn during the time a new lead is inserted;

Fig. 6 is a vertical section taken on the line 6—6 of Fig. 5;

40 Fig. 7 is a perspective view of the push button, the toothed rod and the disengaging bar;

Fig. 8 is a perspective view of the lead encasing shoe with the lead.

45 Similar numerals refer to analogous parts throughout the several figures.

In Figs. 1, 2, 3 and 4 the outer housing or shell is made in two halves 1 and 2, and are united toward the upper end by screws 7, and the lower end is contained in the round counter bore of the collar or lead outlet terminal 8, which has a longitudinal slot of oblong cross section wherefrom to protrude the flat lead 9, sufficiently for 55 writing or marking purposes.

The top portion of the flat lead 9, is held

in place by the fingers 10 (see also Fig. 8), of the metallic shoe 11, which has a rough or slightly corrugated back side 12, and an elastic pawl terminal 13, integral therewith which engages the round rod 14, provided with downwardly pointed ratchet teeth cut tangentially, to a depth of a quarter part of the diameter. This toothed rod 14, can be depressed downwardly in the slot 16 by 60 knob 15, until the bottom 17, of the gap 18, is reached, the height of this gap being equal to the pitch of the teeth on the rod 14.

The slot 19, has an oblong cross section and is divided between the two halves of the shell 1, and 2, and has a rough or slightly corrugated wall 20, which serves as a back adjacent to the rough surface 12, of the shoe 11, during the upward travel of the toothed rod 14, during which time shoe 11, is stationary, thus allowing the elastic pawl 13, to ride freely on the top of the toothed rod 14, as it ordinarily is in the case of ratchets. The upward travel of the rod 14, and knob 15, is actuated by a compression coil spring 80 70 75 21, the lower wire end of which is carried in the recess 22, of the shell 1, and 2, while the upper wire end is fastened in the drilled hole 23, of the rod 14.

When the flat lead 9 is used up and a refill is inserted, the shoe 11, is forced upward until the stop projection 24, is reached. In order to do this it is necessary to disengage the elastic pawl 13, from the teeth of the round rod 14. This is provided for 85 90 as shown in Figures 1 and 4, by simply twisting the push button 15, and the toothed rod 14, approximately 90 degrees, this being ample to free the toothed part of the rod 14, from engagement with the elastic pawl 13, 95 thereby bringing the smooth part of said rod under it.

A limit to the angular movement of the push button 15, is provided for by a stop pin 25 which is driven in the rod 14, and which 100 can alternately touch the stop surfaces 26, and 27 of the recess 28, cut into the shell halves 1, and 2 (see Figs. 1 and 4), said stop pin 25, touching the top wall 29, of recess 28, also limiting the axial upward travel of the rod 14.

The coil spring 21, is not only installed to elevate the rod 14, but also to rotate the same into engagement with the elastic pawl 13.

The arrangement shown in Figs. 5, 6, and 7, showing another embodiment of my in-

vention, also necessitates a pushing down of the button 15, in order to feed the flat lead out of the pencil in a similar way as described and illustrated in Fig. 1, but when inserting a refill into the shoe 11, the release of the same and the disengaging of the elastic pawl 13, from the teeth of the rod 14, originates from a pull exerted on the button 15, instead of a twist as previously described. Fig. 7, indicates the push button 15, the neck 30, of decreased diameter, continuing into the toothed rod 14, which has an increased diameter, thereby forming shoulder 31, with the neck 30. The vertical slide bar 32, and its supporting bracket 33, containing hole 34 is rotationally mounted on the neck portion 30. The two wedge like and downwardly inclined wings 35, of slide bar 32, are slidably incased in pockets 36, see Figs. 5 and 6, having inclined top walls 37, and are located in shell half 1. The coil spring 21, used here is purely a compression spring and keeps the slide bar 32, which is nearly touching the right end of elastic pawl 13, down against the shoulder 31. As soon as a pull is exerted on button 15, the upward moving slide bar 32, is compelled to rotate slightly around the longitudinal center of rod 14, in a counter clockwise direction looking from the top, owing to the travel of the angular and wedge shaped wings 35, on the inclined surfaces 37. This movement finally disengages the elastic pawl 13 from the teeth of the rod 14, and the shoe 11 is free to travel upward until it finally reaches the stop 24, carrying a new inserted lead 9, with it.

Another arrangement in the structure though not illustrated here could be obtained by rigidly connecting the slide bar 32 and bracket 33, as shown in Fig. 7, to the toothed rod 14. In the latter case the wings 35 could be eliminated and a similar partial rotation (counter clockwise when viewed from the top) of the button 15, will again disengage the elastic pawl 13, from the teeth of the rod 14. The slide bar 32 could have a variety of different shapes of cross section, and could even be made integral in one piece with the toothed rod 14.

I claim:

1. In a device of the class described, a shell consisting of two halves, a longitudinal slot of oblong cross section adapted to guide a marking element in said shell in conjunction with a longitudinal slot of circular cross section adjacent thereto, a turnable rod having a ratchet face mounted in said round slot, a tip portion with a collar uniting at one end the two halves of the shell and provided with an aperture aligned with said oblong slot through which to project said marking element, a shoe adapted to grip one end of said marking element, said shoe having a projecting pawl adapted to

engage said ratchet face of said rod, to provide a feeding means to propel the marking element toward the point of the pencil.

2. In a device of the class described, comprising a shell consisting of two halves, a longitudinal slot of oblong cross section formed by the union of said halves and adapted to guide a marking element contained therein, in conjunction with a longitudinal slot of circular cross section adjacent thereto, a ratchet faced rod rotatably and reciprocably mounted in said round slot; a tip portion with a collar uniting at one end the two halves of the shell and provided with an aperture aligned with said oblong slot through which to project said marking element, connecting means between said writing element and said ratchet faced rod, whereby to advance said writing element toward the point of the pencil by reciprocation of aforesaid ratchet faced rod and a means to limit the stroke of said reciprocation.

3. The substance contained in claim 1 and a means to disengage said pawl with said ratchet.

4. The substance contained in claim 1 and a means to limit said feeding means in propelling the marking element, through the aperture contained in the point of the pencil.

5. The substance contained in claim 1 and means to limit the travel of said rod in said round slot whereby to graduate said feeding means which propels the marking element toward the point of the pencil.

6. In a carpenter's tool, comprising a shell consisting of two halves forming interiorly when viewed in cross section a slot of substantially oblong cross section and a circular bore companionable therewith, said slot of oblong cross section adapted to guide a marking element mounted for movement therein, a reciprocable and turnable ratchet faced rod contained in said circular bore, a tip portion with a collar uniting at one end the two halves of the shell and provided with an aperture aligned with said oblong slot through which to project said marking element; a shoe enclosing one end of said marking element and having a detent which is adapted to engage said ratchet faced rod; means to reciprocate said rod whereby to propel said marking element toward the point of the pencil and a means to limit the stroke of which said rod is reciprocated.

7. In a writing instrument comprising a shell composed of two halves cored so as to form when joined together two separate longitudinal communicating chambers, one of which has an oblong cross section, the other a circular cross section, said chamber of oblong cross section adapted to guide a writing member mounted for movement therein, and a ratchet faced rod rotatably and reciprocably mounted in said chamber of circular

cross section, a tip portion with a collar uniting at one end the two halves of the shell and provided with an aperture aligned with said oblong slot through which to project said writing member, means to limit the rotational movement and the reciprocable movement of said ratchet faced rod, and means to connect said writing member with said ratchet faced rod whereby to provide a feeding means to propel said writing member toward the point of the pencil.

8. In a writing and marking instrument comprising a tapered shell, consisting of two halves, a tip portion with a collar uniting the tapered ends of the two halves forming said shell and provided with an aperture, a longitudinal slot of oblong cross section formed by the union of said halves aligned with the aperture contained in said tip portion, said slot being adapted to guide a marking element in said shell in conjunction with a longitudinal slot or circular cross section adjacent thereto, a turnable rod having a ratchet face mounted in said round slot, means to connect said marking element with said ratchet faced rod whereby to provide a feeding means to propel the marking element toward the point of the pencil, means to disengage said marking element with said ratchet faced rod whereby to insert a refill in said oblong slot and means to graduate the feeding means of the marking element.

9. In a writing instrument of the class described comprising a shell body, one end 35 of which is encased in a tip portion provided with an aperture composed of a hard burned porcelain substance, said shell body being made in two halves and united together, each said half being cored so as to form when 40 united, two longitudinal companion chambers, each having an oblong and circular cross section respectively; the chamber having the oblong cross section being adapted to guide a marking element contained in 45 said shell body and aligned with said aperture, a toothed rod reciprocably and rotatably mounted in said chamber of circular cross section, a shoe adapted to grip one end of said marking element, fingers in said shoe 50 for engageably holding said marking element therein, said shoe having formed as a part thereof a detent which is adapted to engage the toothed portion of aforesaid toothed rod, a normally tensioned retractile 55 spring fastened to said rod and recessed in said shell body whereby to produce a rotational means for re-engaging said toothed rod with said detent after partial rotation thereof and also to provide a reciprocable movement for said toothed rod whereby to propel said marking element toward the point of the pencil and a graduatory means for feeding said writing member in said direction.

CHARLES F. HARTMAN.
